UNITED STATES PATENT OFFICE.

MORRIS STEIN AND ABRAHAM S. LEVIN, OF PHILADELPHIA, PENNSYLVANIA.

TWIN COILS FOR ICE COOLERS.

Application filed March 31, 1927. Serial No. 179,887.

It has been the practice heretofore to employ a single cooler coil, the bends or convolutions of which were arranged in a single horizontal plane, resting on the bottom of the cooler chamber or ice box, in which construction said convolutions were liable to be damaged by the impact of a large cake of ice dropping thereon. It has also been proposed to employ a coil having resilient convolutions graduated in height, the lowermost of which rested on the bottom of the cooler chamber, while the uppermost thereof served resiliently to support the cake of ice, thus to obviate any damage to said coil by the weight or impact of the cake of ice in case it slipped during the placing thereof on the upper coil. This necessarily restricts the ice space because of the height of the bends or convolutions exposed to the refrigerating medium, since the helically arranged, separated convolutions occupied a relatively large amount of space within the cooler chamber thereby resulting in a corresponding decrease in space available for ice and necessitating the frequent replenishing of the same.

The object of our invention is to overcome the disadvantages of the prior constructions by providing novel twin coils compactly arranged, whereby a maximum number of bends or convolutions is employed, thereby affording maximum contact with the cooling medium.

Our invention relates to a new and useful twin coil construction for water coolers of the type employing a cooling coil wherein the water to be cooled flows from a city main or other point of supply to the point of use, said coils supporting the cake of ice, and the construction being such that both of said twin coils are at all times submerged in the ice water so that a maximum cooling effect is attained.

To the above ends, our invention consists of twin upper and lower coils, the outer end of the lower coil being connected to a water inlet, while the outer end of the upper coil is connected to a spigot, and a coupling member suitably connecting the juxtaposed inner ends of the lower and upper coils to each other, said upper and lower coils being compactly arranged in only two horizontal planes which are at all times submerged in the ice water, thus providing a maximum surface contact with the refrigerating medium and occupying a minimum amount of

space in the lower portion of the cooler, so that maximum space for ice is provided above the upper of the twin coils.

For the purpose of illustrating our invention, we have shown in the accompanying drawings, a form thereof which is at present preferred by us, since it will give in practice, satisfactory and reliable results, although it is to be understood that the various instrumentalities of which our invention consists may be variously arranged and organized and that our invention is not limited to the precise arrangement and organization of these instrumentalities as herein shown and described. In the accompanying drawings:

Figure 1 represents a perspective view of a water cooler, partly broken away, showing in perspective, our novel construction of twin cooler coils.

Figure 2 represents a side elevation of the twin cooler coils seen in Figure 1.

Figure 3 represents a plan view of the upper cooler coil and its connecting coupling.

Figure 4 represents a plan view of the lower cooler coil.

Figure 5 is a sectional view of the coupling.

Referring to the drawings, in which like reference characters indicate like parts, 1 designates an upper cooling coil having the exit or outlet branch 2, which leads through the wall of the cooler 4 to the spigot 5. The coil 1 as seen in Figures 1 and 3 is composed of three convolutions, but obviously, the number of convolutions can be increased or diminished as desired. The inner end 6 of the upper coil is provided with a coupling 7, whose construction will be understood from Figure 5, said coupling having the horizontal branch 8 connected to the end 6, the intermediate inclined portion 9 and the lower horizontal branch 10 connected with the inner end 11 of the lower coil 12, which latter if desired may be composed of three or more convolutions and is provided with the inlet 13, which communicates with the water inlet pipe 14 by a suitable elbow 15. The two coils 1 and 12 are substantially duplicates of each other and when they are assembled and coupled together by the coupling 7 said coils will be very compactly arranged in two horizontal planes and will appear as in Figures 1 and 2 and the incoming water which enters

through the pipe connections 14, 15, 12 and 13, after passing through the two horizontally disposed coil sections 12 and 1, will be effectively cooled by the time the water reaches the branch 2 and the spigot 5. 16 designates a siphon by which the water from the melted ice is conducted through the drain pipe 17 to any desired point. It will be noted that the inlet end 18 of the siphon, 16 as seen in Figure 1, is located slightly above the upper coil 1, so that both coils will always be at all times submerged in ice water, the cake of ice being supported on the upper coil 1. By the employment of the upper 15 and lower twin coils as seen in Figures 3 and 4 in conjunction with the coupling 7, it will be apparent that we are enabled to position said upper and lower coils very closely together and we are further enabled 20 by our novel construction to have both said coils at all times submerged in ice water and said coils are further, when assembled, very compactly arranged and positioned near the bottom of the cooler 4, so that there is a 25 maximum space provided above the upper coil 1 for the reception of a maximum amount of ice. The cooler in practice is provided with the top 19 having an opening therein for the insertion of the cake of 30 ice and it is supported on legs 20. In placing the ice in the cooler, the ice is introduced through the top thereof and deposited on the upper coil 1, which is of such area, that all the convolutions or bends thereof, 35 in the same horizontal plane are subjected to the cooling effect of the ice and as the latter melts, the cooled water accumulates until it is slightly above the top of the upper coil 1 so that both coils are at all times submerged in ice water, any excess water being 40 merged off through the siphon 16.

By the employment of the coupling 7, having the downwardly inclined portion 9, we are enabled to couple the juxtaposed 45 ends 6 and 11 together so as to position the two coils 1 and 12 in two horizontal planes very close to each other in proximity to the bottom of the cooler, which not only affords a maximum ice space, but permits 50 the entire portion of the two horizontal coils to be at all times submerged in ice water as is evident. The two coils having been positioned in the cooler with the juxtaposed ends 6 and 11 in proximity, the coupling 7 is 55 placed in position and then soldered or brazed in any suitable manner.

It will now be apparent that we have devised a new and useful twin coil for ice cool-

ers which embodies the features of advantage 60 enumerated as desirable in the statement of the invention and the above description and while we have in the present instance, shown and described an embodiment thereof which is at present preferred by us since it will give in practice satisfactory and reliable results, it is to be understood that such embodiment is susceptible of modification in various particulars without departing from the spirit or scope of the invention or sacrificing any of its advantages. 70

Having thus described our invention, what we claim as new and desire to secure by Letters Patent is:

1. A water cooler, comprising an ice box 75 having a water inlet and a water outlet, a lower coil having its convolutions in a horizontal plane and horizontally disposed in said ice box and having its outer end connected to said water inlet and its inner end terminating within the coil, an upper coil superimposed on said lower coil and having 80 its convolutions in a horizontal plane and having its outer end connected to said water outlet and its inner end juxtaposed to the inner end of said lower coil and means connecting the inner ends of said upper and lower coils, comprising a coupling disposed within said coils and having two terminal portions horizontally disposed in different 85 planes and joined by an inclined portion, said terminal portions being secured to said inner ends of said coils, thereby enabling 90 said coils to occupy two horizontal planes in close proximity to each other.

2. A water cooler, comprising an ice box 95 having a water inlet and a water outlet, a lower coil horizontally disposed in a horizontal plane in said ice box and having its outer end connected to said water inlet, an upper coil superimposed on said lower coil 100 in a horizontal plane and having its outer end connected to said water outlet, the inner ends of said coils being in alignment but at different levels, means connecting the inner ends of said upper and lower coils, comprising a coupling disposed within said coils and having horizontal terminals arranged at 105 different levels and connected by an inclined intermediate member, said terminal portions being secured to said inner ends of said coils, and a waste outlet in said ice box, both of 110 said upper and lower coils being disposed in horizontal planes below the inlet of said waste outlet.
